FURNACE DAMPER AND FUEL CONTROL SYSTEM

Norman F. Hahn, Parma, and Arthur A. Kraft, Cleveland, Ohio, assignors to The Cleveland Fuel Equipment Company, Cleveland, Ohio.

Application July 15, 1953, Serial No. 368,154

5 Claims. (Cl. 236—14)

This invention relates to control devices and more particularly to an adjustable means incorporated into a furnace control system to regulate the air that is carbureted with the fuel to produce optimum conditions of combustion.

Control devices used today in both domestic and industrial furnace installations are operable to introduce fuel into the combustion chamber wherein air is combined with the injected fuel, and the mixture is then ignited producing the heat necessary to sustain the operation of the furnace.

The air supplied to the combustion chamber may be controlled by a wafer-type valve, commonly referred to in the art as a damper, which is located in the furnace stack system.

The damper is usually opened just prior to the introduction of the fuel to the combustion chamber, and as a result the draft created is often excessive and the pilot flame is blown out causing the furnace to shut down and continuously recycle. If the damper is opened an insufficient amount, not enough air is allowed to enter the combustion chamber to enable proper purging of the chamber and stack, and upon firing of the fuel any gases that have not been so removed usually result in explosions that may be very detrimental to the furnace or to operators.

Our device comprises a novel means whereby the damper is automatically adjusted to a safe light-up position resulting in a correct predetermined draft for a subsequent igniting of the fuel, and permitting proper purging of the unit without affecting the pilot flame or existing fire bed, and which thereafter modulates the draft.

Further advantages of our invention will be realized by those familiar in the art and a more thorough understanding thereof will result by referring to the accompanying drawing which forms a part of this specification.

Fig. 1 is a wiring diagram shown partly in diagrammatic form illustrating one embodiment of our invention used in conjunction with a typical furnace electrical control system, and Fig. 2 is a plan view showing one structural embodiment of the present invention.

Briefly, our invention comprises switch means 10 that are mounted on a sliding mechanism 11 and movable over the operating range of a thrust arm member 8. The thrust arm 8 moves longitudinally with respect to the switch mechanism, and is adapted to trigger the switch means to control the damper for safe draft conditions.

The furnace construction per se, in which our device is incorporated may be any one of the class of installation well known in the art comprising generally a boiler having a combustion chamber, a burner extending into the combustion chamber and adapted to burn fuel supplied from a fuel reservoir, and a pilot flame or fire bed for igniting the fuel. A stack 25 is connected to the combustion chamber and has a draft damper 9 for regulating the air entering the stack and hence the air in the furnace.

2

Briefly, in operation, the damper control device of the present invention opens the damper 9 to allow air to purge the combustion chamber and stack of any gases that are present as a result of previous firing of the boiler.

5 The draft provided by the opening of the damper is limited by said device to what is commonly known in the art as the "safe light-up position," which position provides a thorough purging of the furnace, without affecting the pilot flame on gas or oil installations, or existing fire bed on coal installations.

A draft indicator 16 which may be located in the stack, determines when a sufficient steady draft has been established, and then signals the electrical control system that it is safe to supply fuel to the combustion chamber. Fuel 15 enters the combustion chamber via burners on oil or gas furnaces, or via a stoker unit to a fire bed on coal burning installations. The pilot flame or existing fire ignites the fuel thereby commencing the burning process.

When it has been definitely established that the fuel 20 is being consumed, a flame detector means 17 signals the electrical control system to begin modulating the draft. A sample of prevailing pressure in the combustion chamber is transmitted to the electrical control system which determines whether there is an excess or deficiency 25 of air in the chamber.

A modulating or balance switch means differentiates the pressure sample, and is adapted to connect electrical energy to the damper control device 2 which opens or closes the damper 9 proportional to the measured pressure, 30 and thereby provides for optimum conditions of combustion. When the heating system has reached its normal operating pressure, a steam pressure switch 4 acts to shut off the fuel supply to the burners, and the electrical control system operates to ready the system for the next cycle. 35

On installations using gas or oil as the combustible fuel, the electrical control system and damper control unit operate to substantially close the damper 9, while on those units utilizing coal, the draft is continuously modulated until the next cycle.

40 More specifically, Fig. 1 illustrates one electrical control system which may be used with the novel damper control device of the present invention. The switch contacts and relay contacts, Fig. 1, are shown in their respective open or closed position which prevails during 45 the standby condition, awaiting a demand for heat. The circuitry to the left of line A—A, Fig. 1, depicts a typical electrical control system, the particular configuration of which may be modified for each furnace installation, and which is not a part of the present invention. The circuitry to the right of line A—A depicts the electrical configuration of the damper control device adaptable to the particular illustrated electrical control system of the furnace.

55 For automatic sequence control, utilizing the illustrated circuit, the selector switch 3 is placed into the automatic position as shown in Fig. 1. The control switch 43 is also placed into the automatic position. When the steam pressure in the boiler falls below a predetermined operating pressure, the pressure switch 4 closes and the coil 41 of relay A is energized through lines 80 and 81. The contact A1 of relay A is then closed, connecting the motor

60 6 to the electrical power source via line 80, through the selector switch 3, line 82, contact A1 of relay A, line 83, contact C1 of relay C, line 84, control switch 43, line 85, contact 44 of bottom adjustable switch 14, line 86, contact 45 of outward limit switch 24, and line 87. The ground 54 provides the return path for said electrical energy as is well known in the art. The motor is connected to a drive screw 7, Fig. 2, upon which is threaded a thrust arm 8 which is moved longitudinally when the motor is energized, rectilinearly with respect to motor 6.

The arm 8 is connected by chain or cable means 32 to the draft damper 9 to open said damper.

An adjustable switch assembly 10 comprising a top and a bottom switch 14 and 31, respectively, mounted juxtaposed to each other on a base 11 which is slidably mounted on an elongated base member 15, is adapted to be positioned on said base 15 anywhere within the path of travel of the thrust arm 8. The position of said assembly depends upon the specific characteristics of each furnace installation and is customarily known in the art as the "safe-light-up" position.

An arm 12 having outwardly extending fingers 13, one being slightly longer than the other, is adapted to slidably engage and operate the adjustable switch mechanism to stop the movement of the thrust arm 8. By making one finger longer than the other, it is possible for the system to be connected so that either the outward or inward movement of the thrust arm will open or close the damper a predetermined amount. We will assume for the sequential operation that the upper adjustable switch 14 on the switch assembly 10 is operated, utilizing the longer of the two fingers, and that the outward thrust of the arm 8 opens the damper.

The motor upon being energized, as described hereinabove, moves the thrust arm 8 outward until the upper switch 14 is triggered by the longer of the two fingers 13 of the lever arm 12, opening contact 44, Fig. 1, whereby the motor circuit is opened stopping the longitudinal movement of the thrust arm. The function of the switch assembly is twofold; it disconnects the motor 6 from the electrical power source, and at the same time it connects the electrical power source to other elements of the control unit for subsequent operation.

When switch 14 is operated by the outward movement of the thrust arm, opening contact 44, the contact 45 of said switch 14 is closed, and energy is fed to contact 47 of the time relay via line 85, contact 46, now closed, line 88, contact 48 of the lower adjustable switch 31, and line 89.

When relay A is first energized upon the closing of pressure switch 4 current is fed to the contact 49 of the draft indicator 16, which is usually positioned in the stack, via line 80, selector switch 3 and line 83.

The draft indicator 16 is of the type commonly known in the art, comprising a wafer or arm that is movable by the air draft in the stack and is operable to open or close a contact 49 carried thereby to make or break a circuit connected thereto. If the draft condition in the stack is insufficient for safe lighting of the fuel, the contact 49 of the draft indicator is closed, and the time delay relay coil 51 is energized. The contact 47 of the time delay relay is opened by the energization of coil 51 thereby preventing any energization of relay B. This circuit condition will prevail until a satisfactory steady draft is maintained, whereby the contact 49 will be opened, allowing contact 47 to be closed after a predetermined delay. The time delay relay may be of the well known clock type whereby a delay period is mechanically incorporated after the electrical energy is removed, after which the contact 47 is allowed to close.

During the period when a sufficient draft is being established, the damper being partially opened, the gases are removed from the stack and fire box.

It was previously mentioned that the outwardly extending fingers 13 of the lever arm 12 were of different length; the reason being, that if on the energization of the motor 6, the arm 8 continues its rectilinear travel after operating the upper adjustable switch 14, the shorter finger will operate the lower adjustable switch 31 which reverses the motor 6 and brings the arm 8 back to the desired position. It is therefore realized that once the "safe light-up" position is determined, the arm 8 will always open the damper 9 to this position on its initial stroke.

After the predetermined delay period, the contact 47 of the time delay relay closes, and electrical energy is fed

to the coil 52 of the relay B via line 85, contact 46, line 88, contact 48, line 89, contact 47, and line 50. Upon energizing relay B, the contact B1 of the relay B is closed, locking said relay in the circuit as long as sufficient draft conditions prevail.

A second (N. O.) contact B2 of this relay B is also closed allowing current to flow through line 80, pressure switch 4, line 81 and line 94 to a fuel feed motor which supplies the fuel to the burners.

10 The pilot flame or existing fire bed ignites the fuel, and the flame detector device 17, of which many various types are well known in the art, the particular device incorporated in the present system comprising a photo electric cell 55 and connected relay 55A having a coil 56 and contact 57, senses a burning of the fuel. The photo-electric cell 55 thereof receives a sufficient intensity of light from the ignited fuel, proving that the fuel has been ignited, and current then flows through said photo cell, and the coil 56 of the flame detector device 17 is energized closing the contact 57 of this relay and connecting the coil 58 of relay C to the electrical power source through line 80, contact 57 and line 93, whereby said coil 58 is energized.

When the coil of relay C is energized the contact C2 of this relay is closed, connecting the electrical power source to a balance switch 1 which modulates the amount of air that is required for optimum fuel combustion.

25 The balance switch 1 comprises a movable contact 61 connected to a diaphragm 19, Fig. 1, which is connected to the power source through line 83, contact C2 of relay 30 C, and line 99. Two stationary contacts 62 are connected to the outward and inward limit switches 24 and 23 respectively, and then to opposite ends of the winding of the motor 6. The upper stationary contact 62 is connected via line 86, contact 45 and line 87, and the lower contact 35 62 is connected via line 91, contact 63 and line 92.

The balance switch is adapted to energize the motor winding in either of two directions to provide reversible energization of the motor. A pressure sample of air taken from the combustion chamber of the boiler through the 40 capillary tube 21, Fig. 1, controls the movement and switching action of the diaphragm 19 and contact 61. In the present circuit, wherein the outward thrust of arm 8 opens the damper, if the air pressure in the combustion chamber is found to be high the diaphragm 19 moves toward the upper stationary contact 62, and when the stationary and movable contacts 62 and 61 respectively, engage, power is transmitted to the motor 6 via line 86, contact 45 of the outward limit switch 24 and line 87 to move the thrust arm outward to open the damper to a greater degree. If the air pressure is found to be low, the diaphragm moves toward the lower contact 62 and when said stationary and movable contacts engage, power is transmitted to the motor 6 via line 91, contact 63 of the inward limit switch 23 and line 92, and the motor then rotates in the opposite direction to move the thrust arm inward to close the damper.

55 The balance switch, by interpreting the pressure conditions within the fire box, is able to accurately regulate the opening and closing of the damper to give optimum fuel consumption and therefore maximum heat transfer within the operational limits of the thrust arm 8.

After the igniting of the fuel has been established, the damper control unit is adapted to cause the thrust arm 8 to travel between its outer limits defined by the inward and outward limit switches 23 and 24 respectively to provide the draft of air required. A finger 26 extends downwardly from lever 12 and is adapted to be in slideable engagement with said said switches to disconnect the motor 6 from the electrical power source.

60 On oil or gas furnace installations, the modulated damping will continue until the system reaches its operative steam pressure, whereupon the steam pressure switch 4 is opened, and relay A is de-energized, stopping the fuel feed. When relay A drops out, the contact A2 of this 75 relay closes, thereby connecting the motor 6 directly to

the electrical power source through wire 80, selector switch 3, wire 82, contact A2 now closed of relay A, wire 72, control switch 43 (in auto position), line 91, contact 63 of inward limit switch 23, and line 92, thereby enabling the thrust arm 8 to completely close the draft damper 9. When the damper is closed, the lever 12 acting through finger 26 actuates contact 63 of the inward limit switch 23 to disconnect the electrical power source from the damper control unit and the electrical control system is then ready for the next cycle.

If the previous firing cycle was performed manually and the damper has been left fully opened, beyond the operating position of the switch assembly 10, whereby the contact 45 of the outward limit switch 24 is opened, and the contact 54 of said switch 24 is closed, it isn't necessary to purge the combustion chamber and stack of captured gases. With these conditions prevailing, electrical energy is supplied directly to contact 47 of the time delay relay, through contact 54, now closed, and wire 89. The fuel is then supplied to the combustion chamber upon draft conditions becoming stabilized, as hereinbefore described. However, under normal conditions, the damper is returned to its fully closed position, wherein the adjustable switch assembly 10 is utilized.

In installation wherein the inward thrust of the arm 8 opens the damper, contact 45 of the outward limit switch 24 is actuated by finger 26 to disconnect the electrical power applied to said damper control device 2.

On furnace installations using coal as the combustible fuel, modulated damping is continued at all times after the initial igniting of the fuel enabling optimum conditions of combustion to be realized.

If it is desired to operate the control unit manually, the control switch 43 is moved to the manual position as shown in Fig. 1 and the selector switch 2 may be manually manipulated to its open opposition or close position whereby electrical power is directed to the motor to open or close the damper. The damper driving unit 2 will operate to open or close the draft damper 9, or if desired, the unit can be disconnected from the electrical power source by moving the switch 3 to the "off" position as shown in Fig. 1.

Having thus described our invention, we realize that extensive departures can be made therefrom without departing from the spirit or scope of our invention.

We claim:

1. In a furnace construction having a combustion chamber, electrically operable fuel feeding means and a burner system for the combustion chamber operable by an electrical control system connected to a source of electrical energy, a stack damper for removal of by-products of combustion and to provide means for an air draft, means for regulating said stack damper comprising a movable member connected to said damper, motive means connected to said movable member, switch means interconnected between said motive means and said electrical control system and operable to define the extreme limits of movement for said movable member and connected damper, switch means interconnected between said control system and said extreme limits switch means and operable to limit the initial opening of said damper, first circuit means in said electrical control system responsive

to a demand for heat from said furnace to connect said fuel feeding means to said source of electrical energy to supply fuel to said combustion chamber, means connected to said fuel feeding circuit means and operable through said electrical control system and both said switch means to energize said motive means to initially open said damper, means attached to said movable member arranged to operate said switch means interconnected between said control system and extreme limits switch means to de-energize said motive means upon the initial opening of said damper to a position intermediate that determined by said extreme limits switch means, second circuit means in said electrical control system including means responsive to the combustion of said fuel and to the combustion chamber pressure and operable to connect said extreme limits switch means to said source of electrical energy whereby said motive means is energized to move said movable member within said extreme limits, said first circuit means being arranged upon satisfying demand for heat to disconnect said combustion chamber pressure responsive means from said extreme limits switch means and to connect said electrical source of energy to said motive means through said extreme limits switch means to close said damper, and means on said movable member operable to engage said extreme limits switch means to disconnect said motive means from said electrical source of energy when said damper is fully closed or fully opened.

2. The device as defined in claim 1, and wherein the switch means interconnected between said control system and said extreme limits switch means are adjustably mounted to be positioned along a path parallel with respect to said movable member.

3. The device as defined in claim 1, and wherein the movable member comprises an arm member connected to the damper and in threaded engagement with the motive means, being rectilinearly movable relative to said motive means.

4. The device as defined in claim 1, and wherein an elongated finger is attached to said movable member and engages and operates said switch means interconnected between said control system and said extreme limits switch means upon movement of said movable member to limit the initial opening of said damper.

5. The device as defined in claim 1, and wherein a pair of elongated fingers, one being shorter than the other, are attached to said movable member and engage and operate said switch means interconnected between said control system and said extreme limits switch means upon movement of said movable member to limit the initial opening of said damper.
